[57] CLAIM

The ornamental design for a combined collapsible beach rest and carrying case, as shown and described.

DESCRIPTION

FIG. 1 is a top plan view of a combined collapsible beach rest and carrying case showing my new design;
FIG. 2 is a front elevational view thereof in the open position;

FIG. 3 is a right side elevational view thereof;

FIG. 4 is a bottom plan view thereof;

FIG. 5 is a rear elevational view thereof;

FIG. 6 is a left side elevational view thereof;

FIG. 7 is a perspective view thereof; and

FIG. 8 is a reduced scale perspective view thereof in the closed position.
